UNITED STATES PATENT OFFICE.

TICE C. KEVITT, OF ATHENIA, NEW JERSEY.

DESIGN FOR A BIRD HOUSE.

Application filed April 2, 1928. Serial No. 26,111. Term of patent 14 years.

To all whom it may concern:

Be it known that I, TICE C. KEVITT, a citizen of the United States, residing at Athenia, in the county of Passaic and State of New Jersey, have invented a new, original, and ornamental Design for a Bird House, of which the following is a specification, reference being had to the accompanying drawing, forming part thereof.

The drawing shows in Fig. 1 a side elevation and in Fig. 2 a plan of a bird house embodying my new design.

I claim:

The ornamental design for a bird house, as shown.

In testimony whereof I affix my signature.

T. C. KEVITT.
